UNITED STATES PATENT OFFICE.

FREDERICK S. PINKUS, OF NEW YORK, N. Y.

DESIGN FOR A SHEET.

SPECIFICATION forming part of Design No. 22,051, dated December 6, 1892.

Application filed October 27, 1892. Serial No. 450,187. Term of patent 14 years.

To all whom it may concern:

Be it known that I, FREDERICK S. PINKUS, a citizen of the United States, residing in the city, county, and State of New York, have invented and produced a new and original Design for Sheets, of which the following is a full, clear, and exact specification, reference being had to the accompanying drawing, forming a part hereof.

10 In the drawing the figure represents a portion of a sheet containing my design.

The leading feature of my design consists in a sheet having a hemstitched border with an ornamental border within the line of hemstitching.

15 The portion of the sheet shown is indicated

at A and the line of hemstitching at B. The sheet itself may be made of any material. Within the hemstitched border is an ornamental figure representing a flowering vine or plant which contains leaves, buds, and blossoms partially opened and in full bloom.

What I claim is—

20 The design for a sheet herein shown and described. 25

In testimony whereof I affix my signature in presence of two witnesses.

FREDERICK S. PINKUS.
